AIR MOTOR FOR A FLOOR POLISHER OR SIMILAR ARTICLE

Lurelle V. A. Guild, Noroton Heights, Conn., assignor
to Electrolux Corporation, Old Greenwich, Conn., a
corporation of Delaware

Application May 21, 1957, Serial No. 46,271

Term of patent 14 years

(Cl. D9—2)

FIG. 1

FIG. 2

FIG. 3

FIG. 4

Fig. 1 is a side elevational view of an air motor for a floor polisher or similar article embodying my new design;

Fig. 2 is a front elevational view thereof;

Fig. 3 is a top plan view thereof; and

Fig. 4 is a bottom plan view thereof.

The side of the air motor for a floor polisher or similar article not shown in the drawings is the same as the side illustrated in Fig. 1.

I claim:

The ornamental design for an air motor for a floor polisher or similar article, as shown and described.
